CLAIM

The ornamental design for a foldable box, as shown and described.

DESCRIPTION

FIG. 1 is a front perspective view of a foldable box; FIG. 2 is a front elevation view of the foldable box of FIG. 1; FIG. 3 is a rear elevation view of the foldable box of FIG. 1; FIG. 4 is a right elevation view of the foldable box of FIG. 1; FIG. 5 is a left elevation view of the foldable box of FIG. 1; FIG. 6 is a top plan view of the foldable box of FIG. 1; FIG. 7 is a bottom plan view of the foldable box of FIG. 1; FIG. 8 is a front perspective view of the foldable box of FIG. 1 in an unfolded configuration; and, FIG. 9 is an exploded front perspective view of the foldable box shown in use with an unclaimed lid. In the drawings, the broken lines form no part of the claimed design.
